UNITED STATES PATENT OFFICE.

HERMAN E. BAUMGARTNER, OF OSAGE, IOWA.

APPARATUS FOR COOLING OR AGITATING AIR.

1,133,255.

Specification of Letters Patent. Patented Mar. 30, 1915.

Application filed December 30, 1912. Serial No. 739,216.

To all whom it may concern:

Be it known that I, HERMAN E. BAUMGARTNER, a citizen of the United States, and residing at Osage, in the county of Mitchell 5 and State of Iowa, have invented a new and useful Improvement in Apparatus for Cooling or Agitating Air, of which the following is a specification.

My invention relates to an apparatus for 10 cooling or agitating air; and has for its object, a device of this class to be used in connection with a fan or the like, and so designed as to cause a current of air to pass through a restricted area at the back of the 15 fan, thence through the fan from where it is circulated.

A further object of my invention is to 20 provide a device of this class with means for preventing the fan from drawing warm air into the current produced, until such current has passed the fan.

A further object of my invention is to 25 provide a device of this class of simple, durable, efficient and inexpensive construction.

The above and other features of novelty, 30 advantages and capabilities of my invention, will become apparent from a detailed description of the accompanying drawings, in which—

Figure 1 is a perspective view of an apparatus embodying my invention; and Fig. 35 2 is a central sectional view of the same, showing a column of ice and fan in place.

Generally stated, my invention consists 40 of a receptacle for holding a column of ice, to which receptacle is secured a vertical shield provided with a central opening of a relatively large diameter, which apparatus when in use is placed at the back of, and adjacent to, a suitable fan, the shield being 45 in a plane at right angles to the axes of the fan. The receptacle is provided with a column of ice and by operating the fan, a current is produced which draws the air over the column of ice, thence through the opening in the shield, thence outwardly past the fan from where it is circulated.

Referring to the accompanying drawings 50 in detail, I have used the reference numeral 55 10, to designate the ice receptacle as a whole. This receptacle consists of an upper and lower compartment, the lower end of the upper compartment being seated within the upper end of the lower compartment, as best shown in Fig. 2. However, I do not wish to limit myself to this particular re-

ceptacle, as any suitable receptacle may be used. The upper part 11, is provided with a dished shaped bottom 12, which bottom is provided with a central opening, through 60 which opening the water passes into the lower compartment as the ice 17, melts. If desired, the lower compartment can, of course, be connected with a suitable drain, and thereby eliminate the necessity of 65 emptying this receptacle from time to time, as would otherwise be necessary.

Secured to the upper compartment 11, of the receptacle 10, is a vertical shield 13, which is provided with a central opening of a relatively large diameter, as best shown in Fig. 1. The shield 13, may be placed adjacent to the receptacle 10, without in any way being connected, but I prefer that it be attached thereto by any suitable means, such as a 75 rivet or bolt. The diameter of the opening in the shield 13, is less than the diameter of the perimeter of the fan, as otherwise the fan blades 18, being larger at their outer ends, than at their center, they would draw 80 warm air, which would increase the temperature of the cool current, and also have a tendency to upset such a current. By providing a shield with such an opening, it also causes the fan to draw the air at a greater 85 velocity over the ice in a smaller space, and thus more rapidly cools the air.

Secured to the shield 13, by any suitable means, is an arch shaped member 15, which serves as a housing for the fan 16. This not 90 only eliminates the danger of one coming in contact with the fan, but also protects to a very great extent the cool current from being interrupted, or its temperature increased by the warm air, until after the cool 95 current has passed the front of the fan, and also facilitates the velocity of the current as by having the housing 15, attached to the shield 13, it makes it necessary that all the air producing the cool current should be 100 drawn through the central opening in the shield 13.

The fan 16, may be of any suitable construction of a convenient size and form, and may be driven by an electric current or any 105 other convenient motive power, or any other suitable means may be used for producing a current, drawing the air over the ice in the receptacle 10, and through the opening in the shield 13, as indicated by the arrows in 110 Fig. 2.

While I have herein shown and described

only one embodiment of my invention, it is to be understood that various changes and modifications may be made by those skilled in the art without departing from the scope 5 of my invention, as defined in the appended claim.

Having thus described my invention, what I claim as new and desire to secure by Letters Patent of the United States, is:—

10 In an article of manufacture, a receptacle, a vertical shield provided with a central

opening attached to and extending above said receptacle, and a protector secured to said shield at the sides and top thereof, substantially as and for the purpose set forth. 15

In witness whereof, I hereunto subscribe my name to this specification in the presence of two witnesses.

HERMAN E. BAUMGARTNER.
